CUP

R. Guy Cowan, Fayetteville, N. Y., assignor to
Onondaga Pottery Company, Syracuse, N. Y., a
corporation of New York

Application December 6, 1949, Serial No. 6,454

Term of patent 14 years

(Cl. D44—9)

To all whom it may concern:

Be it known that I, R. Guy Cowan, a citizen of the United States, residing at Fayetteville, State of New York, have invented a new, original, and ornamental Design for a Cup, of which the following is a specification, reference being had to the accompanying drawing, forming a part hereof.

Figure 1 is a top plan view of a cup disclosing my new design;

Figure 2 is a side elevational view; and

Figure 3 is a partial sectional view thereof taken on line 3—3, Figure 1.

The dominant feature of the design consists in the combination of the handle shaped as shown, and the exterior ornamentation consisting of a raised surface encircling the top of the cup and blending at its upper edge with the rounded lip of the cup and delineating a shoulder at its

lower edge of repeated, oppositely pointed, wide V's connected by sinusoidal curves, as shown.

I claim:

The ornamental design for a cup, as shown and described.

R. GUY COWAN.
